UNITED STATES PATENT OFFICE

2,393,164

ELECTRIC CIRCUIT BREAKER

Leland S. Hobson, Drexel Hill, Pa., assignor to
 General Electric Company, a corporation of
 New York

Application February 27, 1943, Serial No. 477,377

4 Claims. (Cl. 200—144)

My invention relates to electric circuit breakers, more particularly to air circuit breakers of the magnetic blowout type for interrupting moderate voltage power circuits, and has for its principal object the provision of an improved air circuit breaker of the aforesaid type that embodies the interleaving barrier principle of arc extinction that is compact and simple in construction for a given interrupting rating and that is also adapted efficiently to dissipate and disperse the highly heated gases expelled incident to arc interruption from the arc chamber or chute so as to lessen greatly the likelihood of flash-over, or restriking of the arc, at the chute exhaust.

The use of magnetic blowout air circuit breakers comparable in size to oil circuit breakers for interrupting power circuits at distribution voltages, such as 5000 volts, has been made possible by improved arc chute construction. In one well known form of magnetic blowout air circuit breaker, the arc is greatly lengthened and attenuated within the arc chute and cooled throughout its length. This results in a rapid increase of the arc stream resistance so that the current is correspondingly decreased and the power factor greatly improved thereby facilitating interruption at a current zero. However, it has been found in the case of heavy overload and short circuit currents that the highly heated arc gases expelled from the chute sometimes form a conducting path through which the arc may restrike after it has been interrupted within the chute. Such restriking or flash-over at the chute exhaust usually results in failure of the breaker to clear the circuit and damage to other equipment may result therefrom. It has also been found desirable further to lengthen the arc by additional looping thereof between interleaving baffle or barrier structure.

In accordance with my invention, the chute is designed so that there is wide dispersal and dissipation, tending toward rapid cooling, of the arc exhaust gases without sacrificing compactness and the benefits of even greater arc lengthening and attenuation within the chute itself.

My invention will be more fully set forth in the following description referring to the accompanying drawing, and the features of novelty which characterize my invention will be pointed out with particularity in the claims annexed to and forming a part of this specification.

Referring to the drawing, Fig. 1 is an elevational view, partly in section, of an air circuit breaker of the magnetic blowout type embodying my invention; Fig. 2 is a partly sectional end view

of arc chute structure taken along the line 2—2 of Fig. 1; and Fig. 3 is a sectional view taken along the line 3—3 of Fig. 1.

The air circuit breaker illustrated by Fig. 1 is shown, for example, in a form that is particularly adaptable for central stations and sub-stations wherein the circuit breaker unit can be bodily disconnected from the stationary circuit. This form of circuit breaker is generally incorporated in metal clad structure for vertical movement therein. However, since this feature forms no part of the present invention, a complete disclosure thereof is omitted in the interest of clearness.

15 The circuit interrupter comprises essentially means for opening the circuit to form the interrupting arc, and arc extinguishing structure. Specifically, the circuit opening means comprises a relatively fixed contact 1 and a movable contact 2 that is pivotally mounted at 3 on one of the circuit breaker studs and is operated by means of a reciprocally movable rod 4. The operating rod is suitably connected to an actuating mechanism (not shown) for operating the 20 movable contact between closed and open circuit positions. The contacts 1 and 2 are electrically connected to the lower ends of the breaker lead-in conductor studs 5 and 6 respectively which also serve as the breaker terminals. Accordingly, 25 when the breaker is connected in series in a power circuit and the contacts 1 and 2 are separated, an arc may form across the gap indicated.

For the purpose of interrupting this power arc, an arc extinguishing structure, such as the arc 30 chute, generally indicated at 7 is mounted with respect to the contact structure so as directly to receive the power arc which is under the influence of the magnetic blowout fields produced by the coils 8 and 9. The switch contacts and the magnetic blowout structures can assume any 35 preferred form and comprise no part of the present invention so that a brief description will be sufficient. Two magnetic blowout coils 8 (but one is shown) are electrically connected to the conductor stud 5 and to the conducting arc runners 8' so that the arc current (as the arc travels along the runners) flows through the blowout coils, as well known in the art.

40 Normally the current is carried in the closed circuit position of the breaker by the spring biased contact 1', the current being shunted to the arcing contact at 1 upon opening of the breaker. As the arc is drawn by the movable contact 2, it is transferred to the arc runner 9' 45 when it passes the position indicated by Fig. 1

so that the blowout coil 9, which is electrically connected as indicated at 9' to the conductor stud 6, is now also connected in series with the arc current. Accordingly, the blowout coils are energized at an early stage to influence the arc in a well known manner, i. e., to drive it into the chute in an ever expanding loop. It will be apparent, of course, that the blowout field can be utilized in the most efficient manner by disposing iron pole pieces (not shown) that co-operate with the blowout coils in the conventional manner at the outer opposite sides of the arc chute.

The arc chute 7 is designed for interrupting the arc, preferably by lengthening and attenuating it within restricted insulating passages so that the resistance of the arc stream is progressively and greatly increased, as described in Letters Patent 2,293,513, issued August 18, 1942, to L. J. Linde for Electric air circuit breaker. As illustrated by Fig. 1, the arc extinguishing structure according to the present invention is formed as a chute by closely spaced side walls 10 and 11 composed of arc resisting material such as, for example, an asbestos compound or a suitable arc resisting ceramic material. Each side wall of the chute is fan-shaped, as shown, and at its inner side facing the other wall is provided with a plurality of arc baffles, such as rib-like fins or ridges indicated at 10a and 11a. The ridges extend radially from the contact end of the chute and are preferably integral with the chute side walls which are in turn suitably joined and clamped together as halves of the chute. The height and spacing of the ridges, as illustrated by Fig. 3, are such that when the side walls are clamped together, the ridges are interleaved (Fig. 2) in spaced relation with respect to each other, i. e., in staggered relation, so as to form a restricted zigzag passage having alternating salients into which the arc is driven from the entrance 12 of the arc chute.

As clearly shown by Fig. 1, which illustrates but half the arc chute in detail, namely, the side wall 11, the ridges extend longitudinally in spaced radial or diverging relation from the chute entrance to the chute exhaust, so that the salient height of the ridges is in a direction transverse to the direction of movement of the arc as it moves through the chute. For the purpose of properly confining and attenuating the arc near the chute exhaust where the ridges are more widely spaced, I provide a tier of short or "stub" ridges 10b and 11b between the main ridges 10a and 11a, respectively, of the corresponding chute sides. As shown by Fig. 1, two stub ridges are located between the upper diverging ends of each pair of main ridges and these stub ridges extend only part way toward the contact or entrance end of the chute thereby providing adequate space between the converging ends of the main ridges at 12 for free passage of the arc into the chute. It will therefore be seen that the length of the zigzag path for the arc is greatly increased toward the exhaust end of the chute, not only by the fan shape of the chute but in greater degree by the additional looping of the arc by the stub ridges.

Therefore, as the arc is driven by the blowout field into the zigzag space defined by the interleaving ridges, the cross-section of the arc is reduced as the arc more and more assumes a serpentine form. If a heavy current arc is to be interrupted, interruption may not occur until the arc has been moved well into the chute. Up

to the point of interruption, the blowout field continues to move the arc outward through the arc passage, thereby progressively lengthening the path of the arc as the amplitude of the zigzag path becomes greater. The arc is thereby greatly lengthened and attenuated concurrent with very effective cooling as it approaches the exhaust part of the chute due mainly to the large cooling surfaces of both the main and stub ridges. It will also be seen that the radially disposed baffles and fan-shaped chute provide at the elongated chute exhaust increased voltage striking length, thereby reducing the potential gradient and minimizing the danger of flash-over, or restriking of the arc, across the chute exhaust.

For the purpose of retarding or throttling the movement of large current arcs within the chute and for cooling and providing adequate venting area for the arc gases, I provide means disposed at the chute exhaust for restricting or decreasing the venting area. This restriction of the venting area also materially reduces the likelihood of flame-throw from the chute.

In the aforesaid Letters Patent to Linde there is illustrated a muffler for suppressing and confining within the chute heavy overload or short circuit arcs. In this arrangement, the grid-like structure of the muffler also freely vents arc gases generated within the chute, the above-described zigzag arc passage simply opening into the muffler at the chute exhaust. My invention is not limited to a specific form of muffler and by way of example there is shown a curvilinear grid-like cooling and venting arrangement comprising spaced insulating fibre plates 13 disposed between the chute sides edgewise with respect to the flow of exhaust gases and transverse with respect to the general length of the arc between terminals. Between the fibre plates are located metal screens or gauze 14, preferably of good heat conductivity. Forming a part of the muffler is an insulating wedge member 15 composed of hard fibre extending entirely across the exhaust end of the chute at the mid-section thereof, as shown by Fig. 2. This member also extends into the chute to a point adjacent to the ends of a pair of stub ridges, as illustrated by Fig. 1, thereby dividing and deflecting in opposite directions the mass of hot gases expelled from the chute and muffler.

This division, deflection and dissipation of the arc gases is furthermore greatly augmented by the radial arrangement of the main and stub ridges and by the fan shape of the chute whereby the gases are vented along practically a semi-circle of arc. This greater length along the chute exhaust materially increases the effective muffler area and also provides a longer line of contact between the muffler and the end of the chute. As previously pointed out, it is advantageous to have this greater length for reducing the potential gradient so as to reduce the danger of flash-over along this line.

It will thus be noted that the gases are discharged from the chute in widely diverging directions so that they are largely diffused and dissipated instead of concentrating at the exhaust for causing flash-over.

Although I have shown but two tiers of chute ridges, i. e., the main ridges 10a and 11a and the stub ridges 10b and 11b, it should be understood that more than two tiers may be used if desired depending on the size of the chute used, the main consideration being to squeeze and attenuate the arc up to the very exhaust end of the chute.

Otherwise, the interleaving efficiency of the chute would be comparatively poor because wide spaces between the outer ends of the ridges indicate that a large proportion of the chute section is taken up by an arc path component parallel to the sides of the chute and therefore of no interleaving value.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States is:

1. An electric air circuit breaker comprising contacts separable to form an interrupting arc, a fan-shaped arc chute into which said arc is directed, said chute having an approximately semi-circular exhaust opening for venting arc gases generated within said chute, interleaving arc baffles formed wholly of insulating material disposed within said chute extending radially from the arc entrance portion of the chute to form a zigzag path for a single arc and to vent said arc gases in diverging directions radially from the exhaust opening, and interleaving stub baffles also formed wholly of insulating material arranged between said first-named baffles at the exhaust opening of said chute materially to increase the number of loops of said zigzag path for said single arc at said exhaust opening as contrasted with the number of loops of said zigzag path for said single arc near the entrance portion of said arc extinguishing structure.

2. An electric air circuit breaker of the magnetic blowout type comprising contacts separable to form an interrupting arc, an arc chute into which said arc is directed, said chute having a substantially semi-circular exhaust opening for venting arc gases generated within said chute through approximately 180°, interleaving baffles disposed fanwise within said chute arranged to form a zigzag path for a single arc and to vent said arc gases in diverging directions radially from the arc entrance portion toward the exhaust opening, a substantially semi-circular muf-

tier at said exhaust opening, and additional interleaving baffles formed wholly of insulating material arranged in a tier between said first-named baffles and adjacent to said muffler materially to increase the number of loops of said zigzag path at said exhaust opening as contrasted with the number of loops of said zigzag path near the entrance portion of said arc extinguishing structure, said additional baffles being materially shorter than said first-named baffles and more than one additional baffle being provided between each pair of said first-named baffles.

3. An air circuit breaker comprising an arc chute having an arc entrance portion and a curvilinear exhaust opening for venting arc gases from said chute, relatively movable contacts separable at said entrance portion, radially disposed interleaving arc baffles extending fan-wise from said entrance portion toward said curvilinear exhaust opening for interrupting and extending a single arc and dividing and diverting the flow of arc gases from said chute in widely divergent directions, and additional arc baffles formed wholly of insulating material disposed adjacent to said exhaust opening and materially shorter than said first-named baffles considerably to increase the number of loops of said zigzag path for said single arc at said exhaust opening as contrasted with the number of loops of said zigzag path near the entrance portion of said arc extinguishing structure.

4. An air circuit breaker comprising an arc chute having an arc entrance portion and an exhaust opening for venting arc gases from said chute, relatively movable contacts separable at said entrance portion, radially disposed interleaving arc baffles extending fan-wise from said entrance portion toward said exhaust opening for interrupting and extending a single arc and dividing and diverting the flow of arc gases from said chute in widely divergent directions, and additional arc baffles formed wholly of insulating material disposed adjacent to said exhaust opening and materially shorter than said first-named baffles, all of said baffles extending substantially to said exhaust opening.

LELAND S. HOBSON.
